UNITED STATES PATENT OFFICE

160,317

LOCOMOTIVE TENDER BODY

John F. Halbeisen, Detroit, Mich., assignor to
Chrysler Corporation, Highland Park, Mich., a
corporation of Delaware

Application July 20, 1949, Serial No. 4,029

Term of patent 14 years

(Cl. D66—1)

To all whom it may concern:

Be it known that I, John F. Halbeisen, a citizen of the United States, residing in the city of Detroit, county of Wayne, and State of Michigan, have invented a new, original, and ornamental Design for a Locomotive Tender Body, of which the following is a specification, reference being had to the accompanying drawing, forming part thereof, in which:

Figure 1 is a perspective view taken from the front end of a locomotive tender body embodying my design;

Figure 2 is a side elevational view of the locomotive tender body; and

Figure 3 is a top plan view of the locomotive tender body.

The rear end of the locomotive tender body in Figure 1 is substantially plain and the side of the locomotive tender body opposite that shown in Figure 2 is substantially the same as that shown in Figure 2.

The characteristic features of my design reside in the portions shown by means of full lines in the drawing.

I claim:

The ornamental design for a locomotive tender body, substantially as shown and described.

JOHN F. HALBEISEN.
